DESIGN FOR A BASE FOR BAND SAWS

William Lasar, Los Angeles, Calif.

Application August 24, 1945, Serial No. 121,620

Term of patent 7 years

(Cl. D93—3)

To all whom it may concern:

Be it known that I, William Lasar, a citizen of the United States, residing at Los Angeles, in the county of Los Angeles and State of California, have invented a new, original, and ornamental Design for a Base for Band Saws, of which the following is a specification, reference being had to the accompanying drawing, forming a part thereof.

Fig. 1 is a perspective view of a base for band saws embodying my new design.

Fig. 2 is a top plan view of the base shown in Fig. 1.

Fig. 3 is a side elevational view of the base shown in Fig. 1.

Fig. 4 is a front elevational view of the base shown in Fig. 1.

Fig. 5 is a rear elevational view of the base shown in Fig. 1.

I claim:

The ornamental design for a base for band saws, as shown.

WILLIAM LASAR.
